FRICITION SPRING

Louis E. Endsley, Pittsburgh, Pa., assignor to The Frost Railway Supply Co., Detroit, Mich., a corporation of Michigan

Application April 8, 1944, Serial No. 530,139

2 Claims. (Cl. 267—9)

This application is a continuation-in-part of my application Serial No. 491,289 filed June 18, 1943 (Patent 2,356,662, issued August 22, 1944) and relates to friction springs of the form disclosed in said application, wherein the spring comprises a single inner helical coil and a plurality of outer coil sections each of which is so formed and assembled with the inner coil that the turns of the outer coil sections have frictional engagement with the turns of the inner coil.

In springs of this type, commonly used on railway car trucks, there is a tendency for the turns of the outer coil sections to creep on the inner coil, in an axial direction. This tendency usually results from slight imperfections or inaccuracies which are difficult to avoid in springs of this character. Where three frictional outer coils are employed on an inner coil, imperfections in the forming of the coils may cause the two end coils to creep towards the middle coil. When this occurs, the middle coil is at times entirely released, by reason of these two end pressures, from contact with the inner or load coil. This reduces the effectiveness of the spring at least one-third, as a friction-producing medium, and may result in expanding the middle coil radially to an extent that causes it to break, or to so over-strain it that it will have no frictional contact even if the end coils do later work away from the middle coil.

For this reason, it is desirable to have the two end coils creep towards the ends of the load carrying coil, or towards the stop at each end of such coil. When this occurs, only two of the three coils can get in contact when compression of the spring is released. This will depend on which way the middle coil happens to creep under service. In any event, the middle coil will not be crowded and overstrained.

Where two outer friction coils are used, it is desirable to have these two outer coils creep towards the ends of the inner coil, or towards each stop on such coil, thus tending to move the two coils away from each other upon release of load pressure. When only two outer friction coils are employed, a greater friction is produced in a spring of given length; therefore, creepage of the two outer coils towards each other does more damage, by reason of getting in contact with one another at the center of the spring, in that the friction coil turns near the middle of the spring will be distorted radially by reason of this crowding at the inner ends of the outer coils.

My invention has for its object the provision of a friction spring structure having a long coil

in frictional engagement with the turns of a plurality of shorter coils, formed in such manner that creeping will be so controlled that the turns of the shorter coils will return to normal no-load positions upon the removal of load from the spring; or if any creepage occurs, it will be toward the ends of the spring assembly instead of toward the middle thereof.

In the accompanying drawing, Fig. 1 shows the long inner coil upon which the outer coil sections are to be assembled; Fig. 2 shows a completed spring, with the inner and outer coils in assembled relation; Fig. 3 shows a modification of the structure of Fig. 2; and Fig. 4 is a perspective view of a portion of the structure of Fig. 1.

The inner coil 3 is tapered at its endmost turns in the usual manner to provide the desired flat seating surfaces and also has stop shoulders 4 and 5 formed thereon to limit the distance which the outer coil sections 6 and 7 may creep toward the extremities of the inner coil.

The coil 3 may be formed in any suitable manner, as by wrapping it on a mandrel, which mandrel may be tapered slightly to facilitate removal of the coil therefrom. This taper usually need not be more than $\frac{1}{8}$ " in 10" of length. The important feature of my invention resides in forming the coil 3 along such helical lines that the pitch of the coil turns near the ends of the coil gradually increases toward the ends of the coil, in the last one or two coil turns at each end of the spring, where three outer springs are employed. This increased pitch may suitably be of only .02" or .03" in each convolution as indicated in Fig. 1, where the pitch of the turns adjacent to the middle of the coil are indicated by the letter "P" and the increased pitch toward the ends of the coil are shown as P plus .02" and P plus .04".

Where only two outer coils are used, the graduated pitch will be from about the middle to the ends of the inner coil.

The outer coil sections, 6, 7, and 8 will be placed on the coil 3 by a screwing action.

By slightly increasing the pitch of the coil 3 from about the innermost end of each coil 6 and 7 toward the adjacent end of coil 3 in each instance, the outer ends of the coil sections 6 and 7 will not have as great tensional and frictional engagement with the coil 3 as their inner ends. Therefore, any creeping tendency of the coils 6 and 7 will be toward the extremities of the coil 3, a distance limited by the stop shoulders 4 and 5, respectively, instead of the creepage being toward the middle coil 3 and perhaps crowding

and expanding it so far in radial directions that it becomes over-strained and ineffective.

Instead of making the outer coil portion in three sections as shown in Fig. 2, it can be formed of only two sections as shown at 9 and 10 in Fig. 3 which will meet at approximately the middle of the coil 3. In such instance, the increased pitch at the ends of the inner coil will prevent crowding and over-stressing the outer coil turns at the middle of the spring.

The outer coil sections will, in either instance, be preferably so wound as to have the same taper as that of the mandrel on which the inner coil is formed.

I claim as my invention:

1. A friction spring structure comprising an inner coil and a plurality of outer coil sections

threaded on the inner coil, in end-to-end relation, the convolutions of the outer coil sections having their sides partially interposed between the sides of the convolutions of the inner coil, and a plurality of the convolutions of the inner coil, adjacent to each end thereof, being of gradually increasing pitch toward the extremities of the coil.

2. A friction spring structure comprising an inner coil, three outer coil sections arranged in end-to-end relation and having the sides of their convolutions partially interposed between the sides of the convolutions of the inner coil, and one or more of the convolutions of the inner coil at each end thereof being gradually increasing pitch towards its extremities.

LOUIS E. ENDSLEY.
